Patented Feb. 27, 1923.

UNITED STATES PATENT OFFICE.

TIMOTHY V. THOMALL, OF CHICAGO, ILLINOIS, ASSIGNOR TO MILK BOTTLE CRATE COMPANY, OF CHICAGO, ILLINOIS, A CORPORATION OF ILLINOIS.

BOTTLE CRATE.

Application filed October 31, 1922. Serial No. 598,198.

To all whom it may concern:

Be it known that I, TIMOTHY V. THOMALL, a citizen of the United States, residing at Chicago, in the county of Cook and State 5 of Illinois, have invented certain new and useful Improvements in Bottle Crates, of which the following is a specification.

The object of this invention is to provide a bottle crate with supports for the bottles 10 of a strong and substantial construction and which will maintain their shape and position notwithstanding the rough usage to which such crates are subjected.

And a further object of the invention is 15 to dispose and reinforce the bottle supporting wires so that they will always be held taut and rigid in their proper spaced relation to hold the bottles in the crate.

In the accompanying drawings I have 20 illustrated a selected embodiment of the invention and referring thereto

Fig. 1 is a bottom plan view of a crate embodying my invention;

Fig. 2 is a sectional view on the line 2—2 25 of Fig. 1;

Fig. 3 is a detail perspective view.

Referring to the drawings the crate comprises a rectangular frame 5 having a plurality of crossed spacing strips 6 arranged 30 therein to form cells or pockets for the bottles. When these crates are filled with bottles of milk, for example, they are quite heavy and they are often handled roughly and thrown about carelessly when filled 35 with full bottles as well as when filled with empty bottles. The crates are sometimes filled with empty bottles in inverted position and placed in bottle washing machines for washing the bottles.

40 It is essential that the supports for the bottles should be of a strong and substantial character and always maintained in proper spaced relation so that they will not only support the bottles properly but will also 45 space them when inverted in the crate.

It has been customary to provide parallel wires arranged in pairs and properly spaced 50 to support the bottles in upright position resting thereon and also to support the bottles in inverted position with their necks resting on the wires. It has been found that 55 these wires became loosened and displaced so that they will no longer support the bottles in upright or inverted position in the desired and expected manner and I have

provided means for reinforcing and securing the supporting wires so that they will always be maintained taut and in proper spaced relation.

My invention comprises a metal strip 8 secured in opposite walls of the crate by nails 9 or other suitable fastening means and corrugated or upset or bent between its ends to provide upstanding guides 10 which are slotted lengthwise of the strip and transversely of the guides. These guides are preferably arranged in pairs corresponding with the arrangement of the supporting wires so that the supporting wires will engage the guides as shown in Fig. 1 and be reinforced and spaced apart thereby. To hold the supporting wires in their guides I provide a locking wire 12 which rests upon the strip and in the slots and beneath the supporting wires so that the supporting 70 wires and the strip are always maintained in their interlocked relation as shown in Fig. 2. The locking wire 12 is slightly less in length than the distance between the opposite walls to which the strip is fastened 80 so that it can be readily inserted in place and it is of sufficient length to prevent disengagement from the supporting wires by endwise movement.

My invention provides means of simple 85 but strong and substantial construction for reinforcing and strengthening the supporting wires and for maintaining these wires in their proper spaced relation so that they will not be forced apart when bottles are inserted in the crate in an inverted position or otherwise but will always be maintained 90 properly spaced to support and hold the bottles. The construction is simple, the parts can be easily made at low cost and 95 easily assembled and the supporting wires are not only held in place but they are supported and reinforced and strengthened.

I may use one or more of these reinforcing strips as may be found necessary or desirable but I contemplate using only one in a crate for a dozen bottles.

The construction herein shown and described is one which I have tested and used and found to be entirely satisfactory but I 105 appreciate that changes in the form and arrangement of parts and in the details of construction may be made without departing from the spirit or sacrificing the advantages of the invention and I reserve the 110

right to make all such changes as fairly fall within the scope of the following claims. Furthermore I reserve the right to employ the invention in crates or boxes or other devices of any form or construction for holding bottles or other articles and I may use the invention in any numbers that may be required. By the use of the words "bottle crate" herein I desire it to be understood as including any crates or boxes for which the invention may be adapted.

I claim:

1. In a bottle crate, a pair of wires extending across the crate, a transverse strip secured at its ends to walls of the crate and engaged with said wires, and independent means engaged with said wires and with said strip for locking the wires and strip in engagement.
2. In a bottle crate, a pair of wires extending across the crate, a transverse strip secured at its ends to walls of the crate and engaged with said wires, and a locking wire engaged with said wires and with said strip for retaining the wires and strip in engagement.
3. In a bottle crate, a pair of wires extending across the crate, a transverse strip secured at its ends to walls of the crate and having guides engaged with said wires to reinforce and space the same, and means engaged with said wires and with said strip for locking the wires and strip in engagement.
4. In a bottle crate, a pair of wires extend-

ing across the crate, a transverse strip secured at its ends to walls of the crate and bent to form upstanding guides to receive and reinforce and space said wires, and means extending through said guides and engaged with said wires and with said strip for locking the wires and strip in engagement.

5. In a bottle crate, a pair of wires extending across the crate, a transverse strip secured at its ends to walls of the crate and bent to form upstanding guides to receive and reinforce and space the wires, said strip being slotted at said guides, and means seated in said slots upon said strip and beneath said wires for locking the wires and strip in engagement.

6. In a bottle crate, a pair of wires extending across the crate, a transverse strip secured at its ends to walls of the crate and having upstanding guides to receive and reinforce and space the wires, said strip being slotted at said guides, and a wire seated on the strip in said slots and beneath said pair of wires to lock the pair of wires and strip in engagement.

7. In a bottle crate, a pair of wires extending across the crate, a transverse strip secured at its ends to walls of the crate and having upstanding guides to receive said wires, and a wire extending through the upstanding guides and located between the strip and said pair of wires for locking the wires and strip in engagement.

TIMOTHY V. THOMALL.
